UNITED STATES PATENT OFFICE

170,152

COMBINED LAMPPOST AND SIGN

Howard A. Daum, Pittsburgh, Pa.

Application September 17, 1952, Serial No. 21,507

Term of patent 14 years

(Cl. D48—31)

To all whom it may concern:

Be it known that I, Howard A. Daum, a citizen of the United States, residing at Pittsburgh, county of Allegheny, and State of Pennsylvania, have invented a new, original, and ornamental Design for a Combined Lamppost and Sign, of which the following is a specification, reference being had to the accompanying drawing, forming a part hereof, in which—

I claim:

The ornamental design for a combined lamppost and sign, as shown.

HOWARD A. DAUM.
